AUTOMATIC TRAIN PIPE CONNECTOR HEAD

Joseph Robinson, New York, N. Y.

Application January 18, 1939, Serial No. 251,491

3 Claims. (Cl. 285—24)

This invention relates to automatic train pipe connectors, and particularly to the coupling head of such devices. Among the objects is to arrange the gathering means of the head with respect to the point of connection between the head and its yieldable support so that a foundation or plate may be formed or placed on the upper portion of the head to receive a plurality of terminals for electrical conduits. In carrying out this object I move the gathering means downwardly until its horizontal center occupies the horizontal plane in which the center of the port that carries the heaviest separating pressures is located. The arrangement is such that room is permitted below said plate, and above the horizontal center of said gathering means, for the actuating parts of an automatic lock adapted to positively secure mating heads together.

These and other advantages of my improvement will appear from the following description and in the accompanying drawings, wherein like reference characters indicate similar parts, and in which

Figure 1 is a front elevation of my improved connector head;

Figure 2 is a side view thereof from the ball member side;

Figure 3 is a vertical section taken on approximately the line 3—3 of Figure 1;

Figure 4 is a sectional detail showing the ball member 14 resting in its seat in the funnel member 16;

Figure 5 is a plan view of my improvement;

Figure 6 is a horizontal section on approximately the line 6—6 of Figure 1;

Figure 7 is a front elevation of a modification of my improvement, and

Figure 8 is a sectional detail on approximately the line 8—8 of Figure 7.

My improved connector head includes one or more vertically spaced ports 10, 11 and 12, the central port 11 being adapted to receive the forward end of the flexible supporting means of my improvement. In my co-pending application Serial No. 245,841, filed December 15, 1938, a desirable form of such support is disclosed.

The gathering means of my improvement includes a forwardly extending stubby horn or ball member 14 having a curved face 15, and a rearwardly inclined shallow funnel member 16 each spaced on opposite sides of the vertical center of the head. The funnel is provided with a plurality of lugs or bearings 17 which extend inwardly with respect to the opening in the apex of

the funnel and receive the curved face of the ball member 14. The apex of the funnel is provided with an annular bearing 18 which fits with and interlocks with a complementary annular bearing 19 at the base of the curved face 15 of the ball member to prevent lateral shifting of mated heads on the lugs 17. It will be observed that the top 20 of the funnel 16 lies approximately in the horizontal plane occupied by the center of the port or opening 11 of the head, and that the center of the port 12 and the ball member 14 and the apex of the funnel 16 are in approximately the same horizontal plane considerably below the center of the port or opening 11. Dropping the funnel and ball member in this manner provides space at the top of the head for the foundation or base plate 21 in which may be mounted a plurality of electric conduit terminals of any suitable design, and brings the horizontal center of the gathering means into the plane occupied by the horizontal center of the port 12 which carries the heaviest pressures. In cooperation with the interlock of the annular bearings 18—19 described, this arrangement greatly advantages the supporting means of the head by giving it, and the lock hereinafter referred to and contemplated for use with my improvement, vastly increased effect over the heavy separating pressures carried in the port 12. These terminals may be threaded into the openings 22 or otherwise secured therein, or they may be mounted on a plate 23 and removably secured in a frame 24 formed above the top of the funnel as shown in Figures 7 and 8. To supplement the aligning effect of the ball member and funnel, and to insure more accurate engagement of the electric terminals of opposing heads, I provide my improvement with a supplementary forwardly extending guide 25 adapted to mate with a companion bearing or guide 26 on the opposite side 40 of the vertical center line of the head. Preferably these supplemental guides are located in the upper corners of the head, Figure 1.

When coupling under extreme vertical variations the lower edge of the connector heads have 45 a tendency sometimes to foul one on the other. This tendency is effectively overcome by providing my improved head with a vertical guiding or bearing surface 27 located at the bottom of the head and which functions in the manner described in my co-pending application Serial No. 245,057, filed December 12, 1938. Provision is also made for an automatic lock of the type shown in my co-pending application Serial No. 245,841, filed December 15, 1938. This lock is 55

located in bearings 28—29 and moves through the opening 30, Figures 1 and 6, of the ball member into the slot 31 of the funnel and into engagement with the bearing 32, Figures 5 and 6, formed 5 on the funnel to receive it, all in the manner described in my aforesaid co-pending application Serial No. 245,841, filed December 15, 1938.

The modification illustrated in Figures 7 and 8 consists of forming the plate 23 in the shape of 10 a frame 24 and suitably securing in the frame, as by bolts 33, removable bases or plates 23 which carry the electrical terminals. These plates bear against a shoulder 34, Figure 8, formed on the frame to free the bolts 33 of undue strains when 15 mating heads are coupled.

What I claim is:

1. An automatic train pipe connector head, comprising in combination, a coupling face disposed at a right angle to the longitudinal direction of the connector and adapted to make a butt-joint with the face of a mating head, a plurality of vertically aligned fluid conducting ports formed in said coupling face, a rearwardly extending longitudinally shallow funnel member on 25 one side of the vertical center of said face and provided in its apex with a relatively wide opening into which extend a plurality of bearing lugs, and a short stubby forwardly extending hollow ball member on the other side of the vertical center of said face and adapted to cooperate with the funnel of an opposing head to align the heads and adapted to seat on said lugs when mating heads couple, the ball of said member and the apex of said funnel being entirely below the horizontal center of the head and in the plane occupied by the horizontal center of the port in said head in which the heaviest pressures are car-

ried whereby the effective holding force of the connector support with respect to mated heads is materially increased, the shallow longitudinal depth of said ball and funnel members being such as to permit car couplers provided with connectors equipped with said head to approach to the maximum extent towards final coupling movement before the ball and funnel commence functioning as aligning means thereby causing a substantial part of the aligning operation to be 10 performed by said car couplers.

2. An automatic train pipe connector head such as described in claim 1 in which a base plate 15 for receiving electric terminals is provided, which plate extends from the top of said funnel upwardly to the top of said head, distinguished further by the provision between the bottom of said plate and the top of said ball member of bearings and openings for receiving the actuating means of an automatic lock, and by the provision 20 of supplemental aligning means for accurately aligning said ports and said electric terminals when the heads couple, said aligning means including cooperative bearings in the apex of said funnel and on said ball member that are adapted 25 to interlock and accurately align the heads when mating heads couple.

3. An automatic train pipe connector head such as described in claim 1 in which means are provided on the lower side of the head for preventing jamming or fouling of mating heads when coupling under extreme vertical variation, distinguished further by the provision of annular bearings on the ball and funnel member which seat one on the other when mating heads couple 30 to prevent relative shifting of the coupled heads.

JOSEPH ROBINSON.
